UNITED STATES PATENT OFFICE.

CHARLES RAYMOND LADEVEZE, OF PROVIDENCE, RHODE ISLAND.

SAFETY-RAZOR-BLADE HOLDER.

Application filed September 9, 1924. Serial No. 736,707.

To all whom it may concern:

Be it known that I, CHARLES R. LADEVEZE, a citizen of the United States, residing at Providence, in the county of Providence and 5 State of Rhode Island, have invented certain new and useful Improvements in Safety-Razor-Blade Holders; and I do declare the following to be a full, clear, and exact description of the invention, such as will enable others skilled in the art to which it 10 appertains to make and use the same.

My invention relates to improvements in devices having a handle and means for connecting a safety razor blade thereto, so that 15 it may be used for numerous purposes.

The object of the present invention is to provide a new and improved form of blade holder by means of which the blade may be held in any one of a number of positions, 20 according to the work to be performed, the construction being such that the device may be easily and inexpensively manufactured and sold at small cost.

With the foregoing in view, the invention 25 resides in the novel subject matter herein-after described and claimed, the description being supplemented by the accompanying drawings.

Figure 1 is a side elevation partly broken 30 away, showing a safety razor blade held in the improved holder, in one position.

Figures 2 and 3 are fragmentary elevations showing the blade held in two other 35 positions.

Figure 4 is a sectional view on the irregular line 4—4 of Figure 1.

Figure 5 is a transverse sectional view on line 5—5 of Figure 1.

Figure 6 is an elevation of the inner side 40 of one of the blade clamping plates and a portion of one half of the handle.

Figure 7 is a fragmentary perspective view showing more clearly the formation at the outer end of one of the blade clamping 45 plates.

Figure 8 is a side elevation showing a different form of construction.

Figure 9 is an edge view of the device 50 shown in Figure 8.

In the form of construction illustrated in Figures 1 to 7, the numeral 1 designates a preferably flat and straight handle whose front end is directed laterally at an obtuse angle to its body portion as indicated at 2, said handle being formed of two metal strips 3 whose rear ends are secured together by a

rivet or the like 4. The front ends of the strips 3 constitute a pair of blade clamping plates 5 whose side edges are oblique to the handle 1, while their front ends are preferably at right angles to said handle. The inner sides of the plates 5 are formed with opposed pairs of longitudinal grooves 6 along their side edges and are also formed with a pair of opposed transverse grooves 7 at their 65 front ends. Any pair of the grooves is adapted to receive the back 8 of a well known form of safety razor blade 9, so that said blade may be held in any of the three 70 positions shown in Figures 1, 2 and 3. Suitable means, such as the screws 10, are provided to move the plates 5 toward each other to tightly clamp the blade in place.

By placing the blade in the position shown in Figure 1 a perfect tool is provided for 75 cutting out picture mats or pulp back board, or for use in leather working, making stencils, etc. When the blade is held in the position shown in Figure 2, an effective device is provided for peeling vegetables and fruit 80 without waste, for whittling wood, for manuring and for numerous other purposes requiring a sharp blade.

The position of the blade shown in Figure 3 is exceptionally advantageous for scraping 85 hard paint and the like from glass or metal, for removing varnish from wooden surfaces, for scraping paper from walls, etc.

In the form of construction shown in Figures 8 and 9 the two halves 3^a of the 90 handle, and the blade clamping plates 5^a, are formed by bending a single metal strip upon itself, the construction shown in these figures being otherwise identical with that above described, so that further explanation 95 is unnecessary.

It will be seen from the foregoing that a very simple, inexpensive and desirable article has been provided, and as excellent results are obtainable from the details disclosed they may well be followed; however, within the scope of the invention as claimed, minor changes may of course be made.

I claim:

A blade holder comprising a handle having one end directed laterally at an obtuse angle and being split longitudinally to provide two opposed clamping plates, said plates having substantially parallel side edges arranged at obtuse angles with the 100 handle, said plates also having end edges arranged substantially at right angles to the 110

handle, the inner faces of said plates being formed with opposed blade receiving grooves, a pair of such grooves extending along and substantially parallel to each of

the herein-mentioned edges of said plates, all of said grooves extending throughout the entire lengths of such edges whereby a blade

can be slid longitudinally in and out of any pair of grooves, and adjustable means for drawing said plates together to clamp a 10 blade in place.

In testimony whereof I have hereunto affixed my signature.

CHARLES RAYMOND LADEVEZE.
